UNITED STATES PATENT OFFICE.

LEVI N. PARKS, OF WINCHENDON, MASSACHUSETTS.

SPOOL.

SPECIFICATION forming part of Letters Patent No. 597,017, dated January 11, 1898.

Application filed April 23, 1897. Serial No. 633,549. (No model.)

To all whom it may concern:

Be it known that I, LEVI N. PARKS, a citizen of the United States, residing at Winchendon, in the county of Worcester and State 5 of Massachusetts, have invented a new and useful Improvement in Spools, of which the following is a specification, reference being had to the accompanying drawings, forming a part of the same, in which—

10 Figure 1 represents one end of a spool embodying my improvements and represented in side view. Fig. 2 is a central longitudinal sectional view of that portion of the spool represented in Fig. 1, the section being taken on line 2 2, Fig. 1; and Fig. 3 represents a portion of the bolt by which the head is attached to the barrel of the spool.

Similar letters refer to similar parts in the different figures.

20 My invention relates more particularly to an improvement in that class of spools known as "jack-spoons," and in the accompanying drawings, A denotes one end of the barrel, having a hole A' coincident with the axis of 25 the spool and a hole A² extending transversely into the barrel and communicating with the hole A'. One side of the barrel A, between its end and the transverse hole A², is slotted to permit the attaching-bolt B to be 30 inserted into the barrel, and the slot is then filled with a block A³, which is secured in its position. The bolt B is provided with a T-shaped head B', which is contained in the transverse hole A² and serves to hold the bolt 35 from being drawn out of the barrel. The head B' is semicylindrical in shape, with its curved side B² bearing against the side wall of the transverse hole A².

The bolt B is screw-threaded for a portion 40 of its length, as at B³, and is provided with a plain outer end B⁴, projecting beyond the end of the spool and forming a gudgeon upon which the spool rotates.

The end of the barrel A is inclosed by the 45 flanges C' of a disk C, which is in contact with the end of the barrel, and is provided at its center with a screw-threaded hub C², engaging the screw-thread B³. The disk C is provided with spanner-holes C³ to allow the 50 disk to be screwed upon the bolt B and brought into close contact with the end of the barrel

A, thereby drawing the head B' of the bolt firmly against the side wall of the transverse hole A². The head D consists of a circular disk of wood or other suitable material, having a central hole D' to allow the bolt B to pass through and fitting a hub E' on the washer E, which is screwed upon the bolt B, thereby clamping the head firmly between the washer E and the disk C. 55

I am aware that it is not new to unite the barrel and head of the jack-screw by means of a joint-bolt provided with a screw-thread to receive a screw-threaded washer which holds the spool-head in place and having a 60 sleeve or thimble inclosing the end of the barrel, said thimble or sleeve being provided with spurs which enter the head and prevent it from being rotated independently of the sleeve, and I do not claim such, broadly. 65

The opposing surfaces of the washer E and disk C in my improved spool are smooth, thereby allowing the head D to turn on the disk C and the washer E to turn on the head D. The disk C is also provided with a screw-threaded hub which enters the end of the barrel and engages the screw-threaded section 70 of the bolt B, so that in putting the parts together the disk C is first screwed tightly upon the bolt B in order to firmly clamp the end 75 of the barrel between the head of the bolt and the disk C and cause the bolt to be held rigidly in position and coincident with the axis of the barrel before the head D is applied. The head D is then placed over the end of 80 the bolt in contact with the disk C and the washer E is screwed firmly against it, and as the washer E and head D are capable of an independent rotation relatively to the disk C the two screw-threaded hubs C² and E' act as 85 check-nuts to each other when the head is clamped between the disk and the washer. 90

In the drawings I have represented only one end of the spool, as the opposite end is a duplicate. 95

What I claim as my invention, and desire to secure by Letters Patent, is—

1. The combination with the barrel of a spool, of a joint-bolt held concentrically in the end of said barrel, and having a screw-threaded section, a disk provided with a circular flange inclosing the end of the barrel 100

and a concentric screw-threaded hub inserted in the end of the barrel and screwed upon said bolt whereby the bolt and disk are firmly clamped in position, a washer screwed upon 5 said bolt and a head clamped between said disk and said washer and said disk having smooth opposing surfaces, substantially as described.

2. The combination of a barrel, a joint-bolt held in said barrel and having a screw-threaded section, a disk screwed upon said bolt against the end of the barrel, a head held against said disk and a washer screwed upon said bolt outside said head and having a con-

centric hub entering said head, substantially as described. 15

3. The combination of a barrel, a joint-bolt held in said barrel and having a semicylindrical head and a screw-threaded section, a smooth flanged disk screwed upon said bolt, a head placed against said disk and a washer screwed upon said bolt outside said head, substantially as described.

Dated this 10th day of April, 1897.

LEVI N. PARKS.
